(57) **CLAIM**

The ornamental design for the cup holder light, as shown and described.

DESCRIPTION

FIG. 1 is a perspective angled front view of the cup holder light, which embodies my design;

FIG. 2 is a perspective angled rear view thereof;

FIG. 3 is a left side view thereof;

FIG. 4 is a right side view thereof;

FIG. 5 is a front side view thereof;

FIG. 6 is a rear view thereof;

FIG. 7 is a top view thereof;

FIG. 8 is a bottom view thereof; and,

FIG. 9 is a perspective view thereof positioned in a cup holder.

The broken lines in FIG. 9 represent environment and form no part of the claimed design.

1 Claim, 5 Drawing Sheets
